RADIONUCLIDE APPARATUS

James R. Montgomery, St. Louis County, Mo., assignor
to Mallinckrodt Chemical Works, St. Louis, Mo., a
corporation of Missouri

Filed May 2, 1969, Ser. No. 17,001

Term of patent 14 years

Int. Cl. D24—02; G21k 1/00

U.S. Cl. D83—1

FIG. 1

FIG. 2

FIG. 3

FIG. 5

FIG. 4

FIG. 6

FIG. 1 is a view in perspective of radionuclide apparatus embodying my new design;

FIG. 2 is a top plan view of the apparatus of FIG. 1;

FIG. 3 is a bottom plan view of the apparatus of FIG. 1;

FIG. 4 is a front elevation of the apparatus of FIG. 1;

FIG. 5 is a rear elevation of the apparatus of FIG. 1; and

FIG. 6 is a side elevation of the apparatus of FIG. 1 as viewed from either side.

I claim:

The ornamental design for radionuclide apparatus, substantially as shown and described.
